UNITED STATES PATENT OFFICE.

HYMAN KOTLITZKI, OF NEW YORK, N. Y.

DESIGN FOR A PASTRY-FORM.

48,903.

Specification for Design.

Patented Apr. 18, 1916.

Application filed January 12, 1916. Serial No. 71,798. Term of patent 7 years.

To all whom it may concern:

Be it known that I, HYMAN KOTLITZKI, a subject of the Czar of Russia, residing at New York city, in the county and State of New York, have invented a new, original, and ornamental Design for a Pastry-Form, of which the following is a specification, reference being had to the accompanying drawing, forming part thereof.

The figure is a perspective view of a pastry form showing my new design.

I claim:—

The ornamental design for a pastry form, as shown.

HYMAN KOTLITZKI.

Witnesses:

Wm. WEINTRAUB,
HAROLD L. KÜNSTLER.
